UNITED STATES PATENT OFFICE

HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY

CAN BODY FLANGING MACHINE

Application filed August 11, 1928. Serial No. 298,993.

This invention is an improvement in can body flanging machines, and more particularly in machines for simultaneously forming laterally and outwardly bent flanges at the ends of a tubular body.

In the manufacture of cans, tubular bodies are flanged outwardly at each end, and heads are connected to the flanges by seaming the heads thereto. This necessitates the prior formation of the lateral flanges.

One of the primary objects of the present invention is the provision of a machine of the turret type operating continuously, and having means in connection with the turret for seating successive can bodies, and other means moving therewith for expanding the can body ends and afterwards flattening the expanded ends to form the lateral flanges.

Another object is the provision of means to feed from a magazine of superposed bodies, successive bodies to the turret.

Another object is the provision of means in connection with the turret and operated by the movement of the flanging mechanisms into operative position for centering the cans with respect to the flanging mechanism, wherein such centering mechanism engages both ends of the bodies.

Another object is the provision of expanding mechanisms, simultaneously operating on the opposite ends of the bodies held by the turrets, while the bodies are traveling with the turrets.

Another object is the provision in such mechanism of means to first expand the ends, and to afterwards flatten the expanded portions to provide a flange extending at substantially right angles to the axis of the body.

Another object is the provision of a machine of the character specified, relatively simple in construction, and operating automatically to receive the can bodies from the magazine and to deliver them in flanged condition.

With these and other objects in view the invention consists in the construction and novel combination of parts fully described hereinafter, illustrated in the accompanying drawings, and pointed out in the claims appended hereto, it being understood that va-

rious changes in the form, proportion, size and minor details of construction within the scope of the claims, may be resorted to without departing from the spirit of the invention.

In the drawings forming a part hereof:—

Fig. 1 is a longitudinal section of the improved machine.

Fig. 2 is a section on the line 2—2 of Fig. 1.

Fig. 3 is an enlarged vertical section at the bottom of the magazine with the parts in one position.

Fig. 4 is a detail in section of the magazine bottom with the parts in another position.

Fig. 5 is a side view of Fig. 4.

Fig. 6 is a detail in horizontal section at the level of one of the pins.

Fig. 7 is a detail in plan showing the locking mechanism in open position.

Fig. 8 is a front view of one of the flanging devices with parts in section.

Fig. 9 is a detail in horizontal section at the level of one of the flanging mechanisms.

Fig. 10 is an enlarged detail in section at the flanging mechanism showing the completion of the operation.

In the present embodiment of the invention a suitable frame or table 1 is provided, in which is journaled a power shaft 2, having a pinion 3 engaging a gear 4 keyed to the hub of a pinion 5 on a stub shaft 6, and the pinion 50 meshes with a gear 7 on a shaft 8, which is journaled in brackets 9 and 10 mounted on the table.

The bracket 9 is fixed with respect to the table, and the bracket 10 is adjustable thereon. This bracket has a lug 11 extending through a slot 12 in the table top, and the lug has a threaded opening to receive a threaded shaft 13 journaled in bearings 14 and 14a on the underside of the table. The outer end of the shaft is polygonal as shown, to receive a wrench or the like to turn the shaft, and the shaft is held from longitudinal movement by collars 15 on opposite sides of the inner bearing 14, and a similar collar 16 at the outer side of the outer bearing 14a.

A turret is mounted on the shaft 8 intermediate the brackets 9 and 10. The turret includes a split wheel, composed of similar sections 17, each having a hub engaging the

shaft, and the sections 17 abut at their adjacent faces, or are separated from each other, in accordance with the height of the can which is to be operated upon. In Fig. 1, the 5 sections are shown abutting, to operate on a relatively short can body, while in Fig. 3, they are shown separated by a filler 18, to enable the machine to operate on a relatively long can body.

10 Each section 17 is pinned to a wheel 19 keyed to the shaft 8 at the outer side of the section, by means of the pins 20 which pass through openings in the hubs of the sections 17 and engage registering openings in the hub 15 of the wheel 19. Each section has seats 21 in its peripheral edge, and the seats register to receive a can body indicated at 22, of tubular formation, and in the present instance oval in cross section. A pair of centering arms 23 20 is secured to each section 17 at each of the seats. That is, there is provided a pair of centering arms at each face of the turret for each seat. The members of each pair are connected to the section by means of a bolt 25 and nut 24. The bolt is passed from the inner side of the section (Fig. 1), and the head is countersunk in the inner face of the section. The arms, as shown in Fig. 2, lap at their inner ends, and the lapping ends are journaled 30 on an arbor 25, which in turn is mounted on the bolt 24. Thus the arms may swing toward and from each other, and they are normally urged apart at their free ends, that is, 35 into inoperative position by a spring 26 arranged between the arms, the arms being recessed to receive the spring as shown.

At the seats, the adjacent edges of each pair of arms are recessed as shown at 27 to fit a can body 22, and in normal conditions, the spring 26 will hold the arms open. When operating upon longer cans, a filler, such as that shown at 18 in Fig. 3, is arranged on the shaft 8 between the sections 17 of the turret. The filler acts to space the sections 17 apart, and necessary adjustment of the wheels 19 is enabled by the movable bracket 10.

The can bodies are fed to the seats in succession from a magazine supported by a plurality of pairs of shafts or rods 28, which are supported by the brackets 9 and 10, at the tops thereof. The members of the pairs are in alinement, and the adjacent ends of the pairs are spaced apart a distance somewhat greater than the length of the can body to be operated upon. Each pair of rods supports a magazine section 29, the sections being similar, and being held in spaced relation by the rods. Channel plates 30 are mounted on the inner faces of the magazine sections, and the can bodies 22 extend between the channel plates, and lie one above the other in the magazine, as shown in Fig. 2. They are delivered one by one to the turret by the mechanism shown in Figs. 3, 4, 5 and 6. This mechanism includes a rocker 31 arranged be-

low each magazine section. Each rod carries a pair of pins 32 and 33, the pins being at the ends of the rocker, and each rocker is pivoted intermediate its ends, as shown at 34, to a block 35 supported by the adjacent 70 magazine section 29. These pins extend through openings in the channel plates 30, as shown in Fig. 4, and they are spaced apart a distance somewhat less than the long axis 75 of the cross section of a can body.

The pins operate in the manner shown in Fig. 4, in which figure, it will be noticed that the lowermost pins 33 support the lowermost can body by engaging within the open ends thereof. When now the rockers are rocked, the pins 33 will be withdrawn, enabling the lowest body to drop, while at the same time the uppermost pins 32 will be extended into the ends of the succeeding body. The rockers are operated by slides 35a, which are mounted in guides 36 connected to the respective magazine sections.

Each rocker has a pin 37 engaging a notch 38 in the adjacent slide, and a spring 39 is arranged between each slide and the guide in a recess in the guide. The springs act to move the rockers to the position of Fig. 3, which is the normal position of the rockers, and they are moved into the position of Fig. 4, by cams 40 supported in a manner to be presently described, the cams engaging rollers 41 on the slides.

The shaft 8 is rotated continuously, and as each seat receives a can body, it moves on in the direction of the arrow of Fig. 2, and the flanging operation on the ends is commenced. The ends of the bodies are exposed, and a pair of flanging mechanisms corresponding in number to the seats, in the present instance 8, is supported at opposite sides of each seat, the said mechanisms being carried by the wheels 19 before mentioned.

Each of these mechanisms includes a head 42, having a hub portion 43, received in a bearing 44 in a slide 45 supported in a groove 46 extending longitudinally of the wheel on the periphery thereof, and the hub is held in the bearing by a set screw 47. The cam 40 before mentioned, is secured to the outer face of the head. A flanged ring 48 is secured to the inner face of the head, and the flange of the ring overlies the inner face of the head in spaced relation from the periphery thereof to a selected distance from the center. This arrangement leaves the inner face of the head exposed by a circular opening 48a somewhat greater than the cross section of the can, as shown in Fig. 8.

A plurality of expander sections is mounted between the head and the flange of the ring, and each section is movable radially with respect to the head. A spring 49 is arranged between each section and the ring, each spring acting normally to force the section inward.

ly. The inner ends of the sections are concave as shown in Fig. 8, to correspond with the periphery of the can body held in the seat, and the inner end of each section is enlarged, 5 as shown at 51, the enlargement extending on both faces of the section. At the ends of the enlargement the sections are beveled as shown at 52, and in normal position, the beveled surfaces are in substantial contact, so that 10 the enlargements 50 form an oval corresponding to the cross section of the can body.

Before the expander comes into operation as an expander, the centering arms 23 of the seat are moved into the operative position at 15 the left of the magazine in Fig. 2. The centering movement of the arms is provided for by a pair of latches 53 on the adjacent head. The latches of each pair have inwardly extending cam surfaces 54, and the latches are 20 adapted to enter openings 55 in the arms, the cam surfaces 54 acting to force the arms together into centering relation on the can body.

Referring to Figs. 3 and 4, it will be noticed that the channel plates extend low 25 enough so that the turret moves between them, but the flanges of the channel plates are cut away. With this arrangement, when a can body is dropped into a seat, it is carried 30 out laterally from the lower end of the magazine, and as the flanging heads move toward the turret, the centering arms are locked on the ends of the can body. Further inward movement of the heads causes the enlarged 35 portions 50 of the expander sections to engage with the end of the body.

Referring to Figs. 9 and 10, it will be seen that the enlargements 50 which extend on 40 both faces of the expander sections are stepped at the ends adjacent to the turrets as shown at 56, and when the sections are in normal position, these stepped portions of the sections will enter the end of the can body as shown in Fig. 9.

45 The sections are expanded by means of a cam head 57 on the inner end of a sectional shaft 58-58a journaled in the hub 43 before mentioned, and in a bearing 59 on the slide 45. The outer section 58a of the shaft has 50 its inner end reduced as shown at 60 to engage within an axial opening in the inner section, and the sections are pinned together as shown. A flange 61 is provided at the outer end of the inner section 58, and a spring 55 62 is arranged between the flange and the hub 43, the spring acting to normally force the shaft outward. A roller 63 is journaled on the outer end of the outer section and it is 60 adapted to engage a cam 64 on the bracket 10. When the roller engages the cam, the shaft 58-58a will be forced toward the turret, and the head 57 will force the expander sections outward. Referring to Figs. 9 and 10, it will be seen that the inner faces of the 65 enlargements 50 are beveled to cooperate with

the bevel of the head 57. Each head 42 is moved toward and from the turret by means of a cam 65 revolubly mounted about shaft 8 at the outer side of the adjacent wheel 19. The cams are restrained from rotation as by 70 lugs on the adjacent columns 9, 10 suitably engaged with the can bodies. Each of these cams has a cam groove 66 in its peripheral surface, and each slide 45 has a roller 67 moving in the groove.

When the can bodies have traveled with the turret something more than 180°, the centering arms are opened by the withdrawal of the latches 53, and the flanged body is released. A discharge chute 68 is arranged at 75 this point for receiving the bodies and directing them to a suitable place of disposal. The entire operation of the improved machine is automatic, the bodies being delivered to the turret, flanged, and discharged from 80 the turret, by mechanism operated by the rotating movement of the turret.

The operation of the improved machine is 85 as follows. With a supply of can bodies in 90 the magazine and the shaft 8 rotating, as each seat in the turret moves into position beneath the magazine, the lowermost can body is released and drops into the seat. As 95 the turret moves onward, the slides 45 begin to move inward, and the latches 53 operate the centering arms to center the body, and further movement of the slides locks the arms in centering position. The locking means is composed of pins 69 on the flange of the ring 100 48, which engage openings 70 near the free ends of the arms. When the heads are at the 105 ends of the can body, the expander heads 57 are moved inward, by the engagement of the roller 63 with the cam 64, and the expander sections are moved outward, to expand the ends of the body, that is, to bend the material at the ends outward. Continued movement of the heads causes the inner ends of the enlargements 50 on the expander sections to press the 110 outbent ends into close contact with the centering arms as an anvil, and the outbent portions at the ends of the body are flattened into positions at substantial right angles to the axis of the body. As the turret moves onward, the heads are withdrawn, the expanding heads 57 being first released. The withdrawal of the heads releases the centering arms, which open and the body is discharged 115 into the chute 68.

120 It will be apparent from the description that the improved machine includes a conveyor provided with seats for the bodies, and flanging mechanism moving with the conveyor and operated by the movement thereof, and that the said flanging mechanism includes means to form an abutment encircling the can body at a selected distance from the end, and that this means is moved to operative position by the movement of the cooperative flanging means into operative position.

tion. The centering arms provide the abutment, and they are moved into position to co-operate with the expanding and flattening means by the said means. The adjustment 5 of the turret for can bodies of different lengths, is enabled by the adjustability of the standard 10. The fillers to be inserted between the turret sections are themselves sectional, and are held in place by the turret sections and the fixing of the standard 10. The 10 improved machine is adapted to operate on relatively short can bodies, or upon relatively long can bodies.

What is claimed as new is:—

15 1. A machine for flanging the ends of tubular can bodies, including a conveyor having seats for the bodies, and flanging mechanism moving with the conveyor and operated by the movement thereof, centering arms for 20 clasping the end of the body to form an abutment at a selected distance from the end, said arms being pivotally connected and normally spring pressed away from the body, and means cooperating with the arms to first move 25 them into operative position and to afterwards flatten the portion of the body extending beyond the arms into contact with the arms.

2. In a machine of the class described, a 20 shaft, a turret on the shaft consisting of similar sections keyed to the shaft and movable longitudinally thereof, the sections having seats for the can bodies, clamping arms on each section for forming an abutment 35 circling the adjacent end of the body, means for cooperating with the abutments to flange the ends, supports on the shaft for said means, said means being operated by the movement of the shaft, and the support for one of the 40 said means being movable with respect to the shaft to enable adjustment of the turret sections away from each other for different lengths of can bodies, and fillers to be inserted between the sections.

45 3. In a machine of the class described, a pair of pivotally connected centering arms movable to engage about a can body between the ends thereof and to provide an encircling abutment at a selected distance from 50 the end, and mechanism cooperating with the abutment to flange the portion of the body extending beyond the arms, said arms normally spring urged to open position, and 55 means in connection with the cooperating mechanism to move them into operative position.

4. A can body flanging machine comprising a turret having pockets to receive the can, 60 a pair of clamping arms pivotally mounted adjacent to each pocket and having can gripping formations, flanging heads corresponding to each pocket, located at opposite sides of the turret and mounted to rotate there- 65 with, means for advancing and retracting the

heads, and means carried by the heads for operating the clamping arms.

5. A can body flanging machine comprising a turret having pockets to receive the can, a pair of clamping arms pivotally mounted adjacent to each pocket and having can gripping formations, flanging heads corresponding to each pocket, located at opposite sides of the turret and mounted to rotate therewith, means for advancing and retracting 75 the heads, and means carried by the heads for operating the clamping arms, and registering means also carried by the flanging heads and interengaging with the clamping arms to maintain them in clamping position 80 during a flanging action.

6. A can body flanging machine comprising a turret having pockets to receive the can, a pair of clamping arms pivotally mounted adjacent to each pocket and having can gripping formations, flanging heads corresponding to each pocket, located at opposite sides of the turret and mounted to rotate therewith, means for advancing and retracting 85 the heads, and means carried by the heads for operating the clamping arms, flanging elements mounted for radial movement in the heads, and means for moving the elements radially after inward movement of the heads 90 to form the can flanges against faces of the clamping arms.

7. The structure defined in claim 4 with the addition that the can engaging formations of the clamping arms are in half-oval form to maintain an oval can with its long 95 axis in radial position.

8. The structure defined in claim 4 with the addition that the can engaging formations of the clamping arms are in half-oval form to maintain an oval can with its long axis in radial position, and the flanging elements 100 are shaped in accordance with the oval contour of the can body.

9. A can body flanging machine comprising standards, a shaft mounted thereon, spaced head supports slidably keyed on the shaft, flanging heads on the supports arranged in opposed pairs, a two part turret on the shaft with its parts arranged for axial movement in accordance with can 110 length and connected to rotate with the shaft, the turret parts having corresponding can pockets and clamping arms adjacent the pockets, a spacer applicable about the shaft 115 between the turret parts, and means for moving one of the standards to permit turret and head support adjustment.

10. In a can body flanging machine, in combination with a rotary pocketed turret 120 and flanging heads mounted in opposed pairs at opposite sides of the turret to rotate therewith, a supply chute comprising parallel channel guides directed toward the turret, and can feed regulating means comprising 125 rockers adjacent the channel guides, each 130

- rocker having upper and lower pins which are alternately projected into the can path between the guides to alternately engage within upper inner surfaces of oval cans
- 5 moving between the guides and suspend the cans with their long axes vertical, and deliver them singly and successively to the turret pockets.
11. In a can body flanging machine, in combination with a rotary pocketed turret and flanging heads mounted in opposed pairs at opposite sides of the turret to rotate therewith, a supply chute comprising parallel channel guides directed toward the turret, and can feed regulating means comprising rockers adjacent the channel guides, each rocker having upper and lower pins which are alternately projected into the can path between the guides to alternately engage
- 15 within upper inner surfaces of oval cans moving between the guides and suspend the cans with their long axes vertical, and deliver them singly and successively to the turret pockets, and means rotating with the turret to operate the rockers.

12. In a can body flanging machine, in combination with a rotary pocketed turret and flanging heads mounted in opposed pairs at opposite sides of the turret to rotate therewith, a supply chute comprising parallel channel guides directed toward the turret, and can feed regulating means comprising rockers adjacent the channel guides, each rocker having upper and lower pins which are alternately projected into the can path between the guides to alternately engage within upper inner surfaces of oval cans moving between the guides and suspend the cans with their long axes vertical, and deliver them singly and successively to the turret pockets, cam followers connected to the rockers, and cams on the flanging heads to operate the followers and the rockers.

13. The structure of claim 9 wherein a sectional chute is disposed above the turret and connected to said standards, one section of said chute being movable with said movable standard.

Signed at Baltimore in the State of Maryland this 8th day of August, A. D. 1928.

HENRY HERMANI.
